UNITED STATES PATENT OFFICE

ALBERT ADAMS, OF McMECHEN, WEST VIRGINIA

SMOKE CONSUMER

Application filed March 13, 1929. Serial No. 346,692.

This invention relates to steam boilers and more particularly to a smoke consumer adapted to be applied to a steam boiler of the locomotive type and by means of which 5 smoke and other products of combustion may pass from the smoke box at the front of the boiler and be returned to the fire-box and consumed therein.

One object of the invention is to provide an 10 attachment of the character described which may be readily applied to a locomotive of a conventional construction without changing the construction of the locomotive and thereby allow locomotives now in use to be 15 equipped with the improved smoke-consuming device.

Another object of the invention is to allow 20 the engine to be operated in the usual manner if the attachment should become inoperative for any reason or it should be found desirable to temporarily discontinue its use.

Another object of the invention is to cause 25 air to be drawn from the smoke box into a manifold connected therewith and forming part of the attachment and thereby allow a draft to be formed which will cause the smoke and other products of combustion to be withdrawn from the smoke box of the locomotive and delivered to the fire-box for 30 reburning and also provide the necessary draft in order to cause the fire in the fire-box to burn.

The invention is illustrated in the accompanying drawings, wherein—

Figure 1 is a view showing a locomotive in side elevation and having the improved smoke-consuming device applied thereto,

Fig. 2 is a longitudinal sectional view 40 through the forward portion of the locomotive,

Fig. 3 is a transverse sectional view taken on the line 3—3 of Fig. 2,

Fig. 4 is a view looking at the rear of the 45 locomotive and showing the relation of the rear portion of the attachment to the fire-box and fire door,

Fig. 5 is a top plan view of the attachment, and

Fig. 6 is an enlarged fragmentary view

showing the construction of a suction fan forming part of the attachment.

The locomotive, which is indicated in general by the numeral 1, is of a conventional construction and includes the usual smoke 55 box 2, fire-box 3 and boiler 4 through which the flues 5 extend with their forward ends secured in a head 6. The customary exhaust nozzle 7 has been shown in the smoke box and there has also been shown the usual partitions 8 and 9 defining a smoke passage 10 through which smoke and cinders usually pass in order to be ejected from the smoke box through the stack 11 above the nozzle 7. There has also been shown the usual screen 65 12 customarily employed to cause large cinders to be broken into fine particles before leaving the smoke box.

The attachment constituting the subject-matter of this invention includes a manifold 70 13 which is preferably rectangular in cross section and is curved longitudinally, as shown in Figs. 2 and 3, so that it may fit snugly against the under face of the rear portion of the smoke box where it is secured 75 by rivets or equivalent fasteners passed through flanges 14 projecting from the walls of the manifold. This manifold has communication with the smoke box through openings 15 and these openings are normally 80 closed by spring-actuated check valves 16 yieldably held closed by springs 17 which draw them upwardly. It will thus be seen that the openings 15 will be normally closed but may be opened when the check valves 85 are moved downwardly by a draft. A gate 18 which extends transversely in the smoke box is pivotally mounted at one end, as shown at 19, and normally remains in a lowered position in closing relation to the smoke passage 10. A cable 20 which is secured to the gate as shown at 21 extends outwardly through an opening in a side of the smoke box and is connected with a pull rod 22 extending rearwardly along a side of the locomotive and into the cab 23 so that the fireman or engineer can draw upon this rod to raise the gate if it is desired to have the locomotive function in the usual manner with the smoke and other products of combustion 100

passing through the passage 10 and out of the smoke box through the stack 11. A screen 24 is provided in the rear portion of the smoke box above and to the rear of the openings 15 in order to cause cinders passing from the flues 5 to be broken into fine particles and thereby allowed to pass through the attachment without being liable to clog the same.

10 Pipes 25 lead from the manifold 13 and are connected by a bridge plate 26 from which extends a pipe 27 leading rearwardly and communicating with the casing 28 of a suction fan 29. This fan is operated by an electric motor 30 and when it is in operation it creates a suction through the pipe 27, thereby establishing a suction in the manifold and causing the valves 16 to be drawn downwardly so as to uncover the openings 15 and allow smoke, cinders and other products of combustion to be drawn from the smoke box instead of passing from the smoke box through the stack. This smoke and other products of combustion are forced from the fan casing through a pipe 31 to a distributor frame 32 which fits about the fire-box 3 of the locomotive and a tank or large cylindrical chamber 34 is provided intermediate the length of the pipe 31 in order to allow 20 smoke to collect in this chamber if too great a quantity is attempting to pass through the pipe at any time. A pipe 35 leading from a suitable source of air supply communicates with the tank at its forward end so that a jet of air may be fed into this tank and not only assist passage of the products of combustion through the same but also supply air to the fire-box.

40 The distributor frame 32 consists of pipe sections connected by couplings in order to define a tubular frame which is rectangular in shape and of proper dimensions to fit snugly about the fire-box. A yoke 36 which is also formed of pipe extends upwardly from the distributor frame against the rear wall of the fire-box about the fire door 37 and from this yoke and the side portions of the distributor frame extend nozzles 38 which pass into the fire-box through its walls. By this 45 arrangement smoke and cinders will be delivered from the distributor frame into the fire-box where they will be consumed. It will thus be seen that the smoke and cinders instead of passing from the smoke box through the stack 11 may be returned to the fire-box where they will be consumed. This not only eliminates dangers of fires being caused by sparks but also prevents danger of the train crew or passengers being injured by flying sparks. When an engine is standing still, the gate 18 may be opened and allow the products of combustion to pass out through the stack as the engine is not operating under forced draft and little or no 55 smoke will be created.

Having thus described the invention, I claim:

1. In combination with a boiler including a fire-box and smoke box having a partition therein defining a smoke passage through the smoke box, a gate in said smoke box movable into and out of position to block the smoke passage, a manifold beneath the rear portion of the smoke box and communicating therewith through openings in its bottom, downwardly opening check valves for said openings, piping leading rearwardly from said manifold to the fire-box, and nozzles extending into the fire-box to deliver products of combustion back into the fire-box.

2. In combination with a boiler including a fire-box and smoke box having a partition therein defining a smoke passage through the smoke box, a gate in said smoke box movable into and out of position to block the smoke passage, a manifold beneath the rear portion of the smoke box and communicating therewith through openings in its bottom, downwardly opening check valves for said openings, a tubular distributing frame fitting about the fire-box, nozzles extending from said frame into said fire-box, and piping leading from said manifold to said frame.

3. In combination with a boiler including a fire-box and smoke box having a partition therein defining a smoke passage through the smoke box, a gate in said smoke box movable into and out of position to block the smoke passage, a manifold beneath the rear portion of the smoke box and communicating therewith through openings in its bottom, downwardly opening check valves for said openings, and means for conveying products of combustion from said manifold and delivering the same into the fire-box.

4. In combination with a boiler including a fire-box and smoke box having a partition therein defining a smoke passage through the smoke box, a gate in said smoke box movable into and out of position to block the smoke passage, a manifold beneath the rear portion of the smoke box and communicating therewith through openings in its bottom, downwardly opening check valves for said openings, a tubular distributing frame fitting about the fire-box and including an arch extending upwardly against the rear wall of the fire-box about the fire door, nozzles extending from said frame and yoke into said fire-box, and piping connecting said manifold with said frame.

5. In combination with a boiler including a fire-box and smoke box having a partition therein defining a smoke passage through the smoke box, a gate in said smoke box movable into and out of position to block the smoke passage, a manifold beneath the rear portion of the smoke box and communicating therewith through openings in its bottom, downwardly opening check valves for said open-

ings, a tubular distributing frame fitting about the fire-box, nozzles extending from said frame into said fire-box, piping leading from said manifold to said frame, and a fan 5 in said piping for drawing air and products of combustion through the piping from the manifold and smoke box and forcing the same towards the frame.

6. In combination with a boiler including 10 a fire-box and smoke box having a partition therein defining a smoke passage through the smoke box, a gate in said smoke box movable into and out of position to block the smoke passage, a manifold beneath the rear portion 15 of the smoke box and communicating therewith through openings in its bottom, downwardly opening check valves for said openings, a tubular distributing frame fitting about the fire-box, nozzles extending 20 from said frame into said fire-box, piping leading from said manifold to said frame, a fan in said piping for drawing air and products of combustion through the piping from the manifold and smoke box and forcing the 25 same towards the frame, an accumulating tank between the fan and frame, and means for delivering air into said tank.

7. In combination with a boiler including 30 a fire-box and smoke box having a partition therein defining a smoke passage through the smoke box, a gate in said smoke box pivoted to said partition at one side thereof and movable vertically into and out of a lowered position in closing relation to the smoke passage, means for moving the gate upwardly to an open position, a manifold beneath the rear portion of said smoke box and communicating therewith through openings in the bottom of the smoke box, downwardly opening 35 check valves for said openings, a screen in the smoke box above and to the rear of the smoke passage and openings in the bottom of the smoke box, and means for conveying products of combustion from the manifold 40 and delivering the same into the fire-box.

8. In combination with a boiler including 45 a fire-box and smoke box having a partition therein defining a smoke passage through the smoke box, a gate in said smoke box pivoted to said partition at one side thereof and movable vertically into and out of a lowered position in closing relation to the smoke passage, means for moving the gate upwardly to an open position, a manifold beneath the rear portion of said smoke box and communicating therewith through openings in the bottom of the smoke box, downwardly opening 50 check valves for said openings, and means for conveying products of combustion from the manifold and delivering the same into the fire-box.

9. In combination with a boiler including 55 a fire-box and smoke box having a partition therein defining a smoke passage through the smoke box, a gate in said smoke box

movable into and out of position to block the smoke passage, the smoke box having openings in its walls rearwardly of the gate, a manifold communicating with the smoke box through said openings, check valves for said openings, and means for conveying products of combustion from said manifold and delivering the same into the fire-box. 70

In testimony whereof I affix my signature.
